UNITED STATES PATENT OFFICE.

HARVEY S. COOK, OF VALPARAISO, INDIANA, ASSIGNOR TO COOK LABORATORIES, INC.,
OF CHICAGO, ILLINOIS, A CORPORATION OF DELAWARE.

HYPODERMIC SYRINGE.

Application filed August 5, 1922. Serial No. 579,924.

This invention relates to hypodermic syringes, and aims to provide an improved syringe of the kind having or employing a cartridge or sealed medicament-container as a 5 separable operative component.

The invention comprises certain improved features, constructions, combinations and sub-combinations exemplified in the accompanying drawings and particularly pointed 10 out in the annexed claims.

In said drawings:

Fig. 1 is a side elevation of a syringe embodying the invention;

Fig. 2 is an enlarged longitudinal section- 15 al view thereof;

Fig. 3 is a sectional elevation of the front portion of the syringe, the section being in a different plane from that of Fig. 2 to show a lateral slot for insertion of the needle;

Fig. 4 is a fragmentary view in side elevation of the rear end of the cartridge holding barrel;

Fig. 5 is an end elevation of the breech cap, viewed from the front end of the instrument;

Fig. 6 is a fragmentary longitudinal sectional view of the breech portion of a syringe having a slightly modified form of connection between the breech cap and barrel;

Fig. 7 is an end elevation of the barrel portion of Fig. 6;

Fig. 8 is a view like Fig. 6 showing another form of connection between the barrel and cap.

In the drawings, 1 denotes a holder for the cartridge 36. The cartridge may be inserted endwise through the breech end of the holder as hereinafter explained. The cartridge holder is represented by a skeleton 40 barrel comprising cylindric end portions and longitudinal connecting parts or strips 2, there being wide longitudinal sight openings 35 in the opposite sides of the barrel whereby the practitioner may observe the contents 45 of the glass cartridge tube and the position of the piston plug 13 and plunger 12 during the fluid-ejecting operation. At its front end the barrel has a fixed head 3, which may be attached by soldering or otherwise. A 50 hypodermic needle 10 is removably connected with the barrel. The needle is shown as a double-pointed needle having an intermediate enlargement 8, and is held in or by the barrel head 3 in a substantially axial position 55 so that the inner end 9 of the needle

extends into the barrel to pierce the rubber plug 38 in the fore end of the cartridge. The head 3 provides an abutment 5 for the fore end of the cartridge and has a recess 6 providing a seat for the needle enlargement 8. The needle enlargement is shown conically shaped and fits in the said recess which is of corresponding shape and size so that the needle is firmly held and the inner face of the enlargement 8 is substantially flush with the abutment 5. The fore end of the barrel, including its head 3, has a radial slot 4 communicating with one of the sight openings 35. This permits the needle to be positioned in the cartridge-holder by passing the longer or outer branch 10 of the needle through the slot 4 while passing the needle enlargement 8 and its inner branch 9 through the sight opening, and then moving the needle longitudinally to lodge its 75 enlargement 8 in the recess 6 of the barrel head. Thus the needle may be easily and quickly positioned. As explained in my application Serial No. 540,628 filed March 2, 1922, the needle may be taken from an aseptic container by means of a cork sealing the container and in which the outer point of the needle is inserted, said cork serving as a handle by which the needle may be manipulated to insert it laterally into the cartridge-holder and then to position it, after which the cork may be removed, thus avoiding possible contamination by contact with the practitioner's fingers.

The cartridge may consist of a straight 90 glass tube having the pierceable plug 38 in its fore end and having a piston plug 13 in its opposite end, these plugs being preferably of rubber or other suitable material and tightly fitted or compressed in the ends 95 of the tube to provide effectual sealing closures or stoppers. Between the plugs is confined the solution of anesthetic or other medicament to be dispensed. The plug 38 is shown having an inwardly facing axial recess, facilitating the piercing of the plug by the needle, while promoting effectual sealing of the cartridge under the conditions of high pressure which may be created during ejection of the medicament. Said plug 38 is 100 so placed that when the cartridge is in correct position the outer face of the plug will bear on the abutment 5 and inner face of the needle enlargement 8, thus holding the needle seated by contact of the fore end of the 110

cartridge with the needle enlargement. The piston plug 13 may be a composite plug, formed of joined sections of rubber and cork, the rubber section being innermost because 5 less liable to be attacked by the medicament, and the cork section being the larger of the two to economize on rubber.

The barrel has near its rear end a finger piece 7 which may be grasped by the fingers 10 while pressing with the thumb on the knob 15 of the plunger rod 14 to push the piston plug 13 into or through the cartridge tube to expel the medicament through the needle. The barrel has a removable breech cap 17 15 longitudinally bored to provide a guide for the plunger rod 14, and which also serves to hold the cartridge 36 in place. Said breech cap has a hub 27 the inner end of which bears against the rear end of the cartridge 20 tube. In this hub is a recess 22 for the plunger head 12 and the bore 23 for the plunger rod. This bore may be lengthened by a small diameter hub 18 on the outside of the cap 17. The removable breech cap 17 25 and plunger connected therewith may be handled as a unit because the outer end of the plunger rod 14 is threaded to receive the knob or thumb-piece 15 after the rod has been passed through the cap. The cap 30 17 may be removably secured to the barrel in various ways. In Fig. 2, the cap 17 has an internally beaded flange 39 which engages an annular groove 19 in the barrel (Fig. 4). Said flange 39 is thinned by an external 35 groove 28 and an internal groove 29, and as shown in Fig. 5 the said flange 39 is divided into a number of parts 21 by slots 20. By virtue of the grooves 28 and 29 the said parts 21 are somewhat elastic so that the flange may easily slip over the barrel end 40 and snap into the groove 19 to hold the cap in place. The hub 27 may have its front edge beveled or rounded and the inside of the barrel may be similarly shaped to assist 45 in the easy admission of the hub into the barrel as the cap is pressed home to move the cartridge into its operative position.

A slightly modified construction for retaining the breech cap in position is shown 50 in Figs. 6 and 7. In Fig. 6, the inside of the barrel is slightly enlarged at 24 and the rear end of the barrel is longitudinally divided into elastic parts 26 by a number of slots 25. Each of the parts or fingers 55 26 has the same kind of an external groove 19 as in Fig. 2, into which the inner bead of the flange 39 of the cap 17 rests to hold the parts assembled. Still another construction is shown in Fig. 8. In this figure, the hub 60 27 of the breech cap has a portion 31 of enlarged diameter to fit in the enlarged diameter 24 of the barrel. The barrel in this instance has the elastic fingers 33 with bent ends 34 to snap into the groove 32 of the 65 breech cap, which is shown having a milled

flange 30. Whichever of the constructions is used, the breech cap can be applied very quickly and without considering its angular relation to the barrel itself. A turning of the cap on the barrel will not tend to loosen it as may be the case with certain other types of connections.

The operation of the syringe is very simple. The needle is first positioned as shown in Fig. 2 and then the cartridge is 70 inserted through the opposite end of the barrel, the breech cap having been first removed. The hub of the breech cap is then inserted into the barrel against the rear end of the cartridge, and the cap is then pressed 75 into place, thus forcing the cartridge lengthwise against the needle. This causes the inner end of the needle to pierce the recess plug 38, and immediately the syringe is ready for an injection administration. A 80 pressure of the thumb on the thumb-piece 15, as the syringe is held by the projections 7, forces the plunger rod 14 forward, thus carrying the plunger 12 with its concave face 16 against the piston plug 13. As the 85 pressure is continued the plug 13 moves forward through the cartridge tube toward the recessed closure 38 until the fluid is expelled, partially or entirely. In this 90 action the plunger 12 by virtue of its concave front face 16 engages the piston plug 13 near its circumference, tending to prevent side spread of said plug and thus avoiding or reducing liability of cartridge breakage.

It will be seen that the described construction permits quick assemblage of the syringe organization, and provides an organization of efficient character whereby injections may be safely administered. The invention is not limited to the particular embodiment 105 shown, and its respective features are useful in various different combinations and sub-combinations.

A syringe cartridge or sealed medicament package comprising a tube having sealing plugs or stoppers in its opposite ends, one to be pierced by a needle and the other to be forced inward to eject the fluid, said pierceable stopper being a recessed rubber plug of substantially the same kind, form and arrangement as the recessed pierceable plug herein shown and described, is the subject-matter of and broadly and specifically claimed in my pending application filed July 1, 1921, Serial No. 481,997. A syringe 110 comprising or embodying such a cartridge or a cartridge characterized by such a pierceable recessed stopper, with means associated therewith to provide an injection-administering organization, including a removably mounted needle to pierce such recessed pierceable stopper, is subject-matter disclosed in said application Ser. No. 481,997 115 and in my pending application Serial No. 11,707 filed February 26, 1925 as a continua- 120

tion of an application filed by me April 8, 1921, Serial No. 451,680½, which syringe or subject-matter is broadly and specifically claimed in my said application Serial No. 5 11,707, the claims therefor being transferable to said application Serial No. 481,997. Therefore such a cartridge and syringe embodying the same are not claimed herein broadly or otherwise than in connection with 10 specific characteristics of the present invention as recited in the appended claims.

What I claim is:

1. In a hypodermic syringe comprising, in combination, a body; a medicament dispensing package insertible in said body; said package including a glass tube, and resilient plugs sealing opposite ends of the tube, one of said plugs being slidable through the tube to dispense the medicament; a canula carried by the body and directed inwardly and having a point to pierce the plug which is opposite the slidable plug; and a plunger movable into contact with said slidable plug and having its inner end provided with a cavity 25 into which the slidable plug may expand to minimize breakage of the glass tube by radial expansion of the plug caused by the plunger; said cavity also permitting the canula to pierce the slidable plug, when it 30 has been thrust hard against the initially pierced plug, without breaking the point off.

2. A hypodermic syringe comprising, in combination, a medicament cartridge; a barrel capable of being opened for insertion of the cartridge; a double pointed hypodermic needle having an enlargement intermediate its ends and seated upon the barrel; and a closure for the barrel designed to retain the cartridge in position without substantial longitudinal movement; said positioned cartridge holding the needle seated by contact 40 of one end with the needle enlargement.

3. A hypodermic syringe comprising, in combination, a medicament cartridge; said cartridge having a resilient plug sealing one end; a barrel, one end of which is open for insertion of the cartridge and the other end of which provides a stop for said cartridge; a needle having an enlargement seated in 50 said other end of the barrel; and means constructed and arranged to retain the cartridge in position without substantial longitudinal

movement; said cartridge in turn holding the needle in place by contact of its end plug with said enlargement.

4. A hypodermic syringe comprising, in combination, a body; a medicament dispensing container constructed to hold a supply of medicament and to be held within said body; a double ended hypodermic needle, the inner point of which is constructed and arranged to pierce said medicament container; said body having a seat at one end for a part of the needle; the body having an opening into which the needle may be moved laterally to be seated without contamination by contact with the walls of the syringe; the syringe parts being constructed and arranged, when in operative position, to hold the needle seated and substantially immovable.

5. A hypodermic syringe comprising, in combination, a syringe body; a medicament-containing cartridge constructed and arranged to have its interior volume reduced and to be held by the body; a plunger on the syringe body for operating the cartridge; and a syringe head closing an opening at the end of the body and slidably receiving the plunger; said syringe head being held upon but quickly detachable from the syringe body by means of resilient fingers carried by one of said elements and snapping into an annular recess provided on the other element; and means for securing an injection needle at the opposite end of the syringe.

6. In a cartridge syringe, a cartridge-holding barrel in which the cartridge is insertable endwise through the breech end; said cartridge being of less length than the barrel; a cartridge-piercing needle removably secured to the fore end of the barrel; and a removable plunger-carrying breech head detachably secured to the rear end of the barrel, said breech head having an extension in the barrel bearing against the butt end of the cartridge; whereby the breech head when being applied pushes the cartridge forward by said extension, and when the breech head is in place the cartridge is held substantially against longitudinal movement between the fore end of the barrel and the said extension of the breech head.

In testimony whereof I affix my signature.
HARVEY S. COOK.
